UNITED STATES PATENT OFFICE.

WILLIAM A. ECKERT, OF BUFFALO, NEW YORK.

SIGNAL-CONTROLLING MECHANISM FOR AUTOMOBILES.

Application filed December 9, 1926. Serial No. 153,688.

This invention relates to a signal mechanism for automobiles which is adapted to be mounted on the post and column of the steering mechanism and so organized that 5 switches may be closed for lighting lamps indicating an intention to turn either to the left or to the right, and to automatically open the respective switch which has been closed so as to extinguish the lamps associated therewith 10 when the turn of the vehicle in a particular direction has been completed.

One of the objects of this invention is to provide a signal mechanism of this character which will enable the driver after having 15 closed a switch and lighted lamps indicating an intention to turn in a certain direction to turn a limited extent in said direction and back to straightaway position without opening the switch and extinguishing the 20 lamps before actually making the complete turn, and also compensating for lost motion in the steering mechanism of the car.

Another object of this invention is to provide an improved switch for a signal mechanism of this character which will be yieldingly and reliably held either in its closed or 25 its open position and which after being moved past a dead center in either direction will quickly complete the movement under 30 spring pressure.

Further objects of this invention are to simplify the construction, reduce the cost of manufacture, and prevent improper manipulation of the signal so as to ensure giving the 35 signal intended.

In the accompanying drawings:

Figure 1 is a fragmentary side elevation of the post, column and wheel of an automobile steering mechanism equipped with my improved signal mechanism. Figure 2 is a front view of the same, partly in section, the 40 sectional part being taken on line 2-2, Fig. 1, looking rearwardly. Figure 3 is a longitudinal section taken on line 3-3 Fig. 1, looking 45 forwardly. Figure 4 is a section view taken on line 4-4, Fig. 3, showing the parts in the normal or neutral position. Figure 5 is a cross section taken on line 5-5, Fig. 3, looking upwardly. Figure 6 is a view similar to 50 Fig. 4 showing the outer locking rail in addition to the tumblers of the signal mechanism. Figure 7 is a similar view showing the outer locking rail and the tumblers in a set position. Figure 8 is a fragmentary longitudinal

position, on an enlarged scale, taken on line 55 8-8 Fig. 7. Figure 9 is a view similar to Fig. 4, but showing restoring the tumbler in the position in which it has shifted the trip lug into position for subsequently opening the lamp switch. Figure 10 is a fragmentary 60 longitudinal section, on an enlarged scale, taken on line 10-10 Fig. 9. Figure 11 is a view similar to Fig. 9 showing the position of the tumblers and the trip lever during the first part of the return movement of the steering wheel to its straightaway position. Figure 12 is a fragmentary longitudinal section, 65 on an enlarged scale, taken on line 12-12, Fig. 11. Figure 13 is a view similar to Fig. 11 showing the trip lever restored by the restoring tumbler to its normal position upon 70 turning the steering wheel while the switch has been shifted into an open position. Figure 14 is a fragmentary longitudinal section, on an enlarged scale, taken on line 14-14 Fig. 13. Figure 15 is a cross section similar 75 to Fig. 5 but showing another relative position of the parts. Figure 16 is a fragmentary longitudinal section, on an enlarged scale, taken on line 16-16 Fig. 5. Figure 17 is a 80 view similar to Fig. 16 showing a different relative position of the parts. Figure 18 is a longitudinal section taken on line 18-18 Fig. 16. Figure 19 is a longitudinal section taken on line 19-19 Fig. 17. Figure 20 is a front 85 view of the steering column, post and wheel and the controlling mechanism mounted thereon, and parts thereof being broken away to show the internal structure. Figure 21 is a perspective view of a supporting plate 90 forming part of one of the switches. Figure 22 is a similar view of the movable contact of one of the switches. Figure 23 is a similar view of the detent of one of the switches.

Similar characters of reference indicate 95 like parts in the several figures of the drawings.

Although my improved signal mechanism may be installed on any available relatively 100 movable parts of an automobile steering gear the same in the present instance is shown in connection with a steering post 30 which is rotatably mounted on a stationary tubular column 31 and provided at its upper end with a hand wheel 32.

The mechanism for controlling the signal is mounted on the upper parts of the steering column and the hub 33 of the hand wheel 105

which turns with the steering post. As an example of a signal suitable for use in connection with this controlling mechanism that shown in Fig. 20 comprises two electric lamps 34, 35 adapted to be mounted on the left and righthand sides of the front part of the car, two lamps 36, 37 adapted to be mounted on the left and right sides of the rear part of the car, the left side lamps being connected 10 in series in one circuit and the right lamps being connected in series in another circuit, a battery 38 or other source of electricity having one pole connected with one end of the circuits of both series of lamps while the 15 other pole of this battery is grounded on some metallic part of the steering mechanism, and left and right hand switches for closing said lamp circuits independently of each other, each switch including a relatively fixed contact 39 which is connected with the opposite end of the respective circuit containing one 20 series of lamps, and a movable contact 40 which is grounded on the car and is adapted to be engaged with and disengaged from the 25 companion stationary contact. Each of the movable contacts 40 is preferably constructed in the form of a rock arm which has a hub 42 mounted on a rock shaft 43 so as to be compelled to turn with this shaft, for which purpose 30 the hub 42 has a square hole 44 and fits on a corresponding shaft part 45 of the switch shaft 43, as shown in Figs 18 and 19. Each fixed contact 39 is preferably constructed in the form of a spring finger, one end of 35 which is secured to a metal supporting plate 46 while its opposite end projects through an opening 47 formed partly in this supporting plate and partly in an insulating plate 48 to which the supporting plate and fixed contact 40 are secured so that the free end of the 40 contact spring is in the path of the movable contact. Upon turning the switch shaft in one direction the movable contact engages the fixed contact, as shown in Fig. 19, and closes 45 the electric circuit containing one series of lamps for lighting the latter, and upon turning this shaft in the opposite direction the movable contact will be disengaged from the fixed contact, as shown in Fig. 18, thereby 50 breaking the circuit of the respective series of lamps and extinguishing the same. Each of the supporting plates 46 preferably has that end of a circuit wire, opposite to the battery, secured thereto by a binding screw 55, thereby permitting of conveniently connecting up the wiring of the signal system. The two switch shafts are arranged in a radial position relatively to the steering post and column and on substantially diametrical- 60 ly opposite sides of the latter and each shaft is journaled in inner and outer bearings 51, 52 mounted in a block 53 which is secured to a supporting casing or body 54 having preferably the form of a split collar the sections 65 of which are clamped against opposite sides

of the column by screws 55. The shafts may be turned manually by any suitable means, for example, by means of handles or finger pieces 56 secured to the outer ends of the same as shown in Figs. 3, 5, 15, 16, 17 and 20. 70

Snapping means are provided which embody my invention whereby each switch shaft is yieldingly held in one extreme or the other of its rocking movement and also assist in effecting the last part of the rocking movement of the switch shaft in either direction, thereby ensuring proper opening and closing of the switches. Each of these snapping means comprises a tension dog 57 having a cam rounded face 58 engaging a correspondingly cam or rounded face 59 on the opposing side of the rock arm 40 and provided with a tubular hub 60 which slides lengthwise on the switch shaft and held against turning by a longitudinal guideway 61 which receives the outer end of the dog 57 and is formed on the adjacent part of the bearing 52, as shown in Figs. 16 and 17. The dog is yieldingly pressed against the contact arm 40 by a helical spring 62 surrounding the switch shaft and engaging with one end against the bottom of a pocket 63 in the bearing 52 and with its other end against the outer side of the hub of the tension dog. When the switch shaft is turned into an extreme position in which the switch is open, as shown in Figs. 16 and 18, the contact arm 40 is out of engagement from the contact spring 39 and the tension dog bears on one side of the highest part of its rounded face 58 against one side of the highest part of the rounded face 59 of the contact arm 40, thereby exerting a wedging or cam action on the contact arm which operates to yieldingly hold the switch in its open position. Upon turning the switch shaft forwardly or in the direction for closing, the switch cam or rounded face 59 of the switch arm by its cam or wedge action on the tension dog causes the latter to be forced longitudinally outward against the resistance of the spring 62 until the highest part of the cam face of the contact arm has passed the dead center or highest part of this cam face 58 on the tension arm, after which the resilience of this spring assists in completing the throw of the switch shaft and effecting a quick closing of the switch, as shown in Figs. 17 and 19, by those parts of the cam face on the tension dog acting on those parts of the cam face of the contact arm on the opposite side of its salient. The switch is now yieldingly held in its closed position until the switch shaft is again turned in the opposite direction when the operation is reversed in the manner just described. 110

By these means of operating the switches the same are shifted easily, promptly and certainly and reliably held in either an open or in a closed position.

The mechanism for controlling the opera- 130

tion of the right and left hand switches is constructed as follows:

Arranged above the stationary supporting body is a rotary carrier 64 which turns with the steering post and hand wheel and is preferably divided into two sections which are connected by screws 65 and secured to the hub of the hand wheel by a set screw 66. On its underside the rotary carrier is provided with two locking rocking rails 67, 68 which are arranged concentrically above the inner ends of the shafts. The inner one 67 of these locking rails forms part of the mechanism which controls the righthand switch and is provided with a downwardly opening releasing gap or notch 69, while the outer rail 68 forms part of the mechanism which controls the left hand switch and is provided with a downwardly opening releasing gap or notch 70, as shown in Figs. 5, 6, 7 and 15. Each of the switch shafts is provided on its inner end with three tumblers which are arranged in different positions around the respective switch shaft and perform different functions depending on the position into which the several tumblers are turned with this shaft. These tumblers comprise a locking tumbler 71, a restoring tumbler 72, and a clearing tumbler 73. The locking tumbler of the left hand switch shaft is arranged below the outer locking rail 68 and adapted to co-operate therewith and the locking tumbler of the right shaft is arranged below the inner locking rail 67 and adapted to co-operate therewith. On diametrically opposite sides of the rotary carrier the same is provided with tripping devices between the inner and outer locking rails and as the construction of the same and their co-operation with the restoring and clearing tumblers of the respective switch shafts is alike, the following description of one tripping device will apply to both:

The numeral 74 represents a restoring tappet which is adapted to engage the restoring tumbler of one of the switch shafts and turn the latter in the direction for opening the respective switch. Adjacent to one side of the restoring tappet is arranged a clearing cam 75 which is adapted to be engaged by the clearing tumbler 73 of the respective shaft for retracting the respective restoring tappet out of its operative position after the restoring tappet has performed its function of extinguishing the lamps. The companion restoring tappet and clearing cam are arranged on a restoring lever 76 which is pivotally mounted on the carrier between the locking rails by a radial pin 77. The numeral 78 represents a setting lever which is pivotally mounted on the carrier between the rails by a radial pin 79 and provided on its front arm with a setting cam 80 which is adapted to be engaged by the respective restoring tumbler 72 while the rear arm of this lever is connected with the restoring lever so that the same rock to-

gether, this last mentioned connection being preferably effected by a knuckle 81 on the rear arm of the setting lever engaging with a socket 82 in the front end of the respective restoring lever, as shown in Figs. 4, 9, 11 and 13. The restoring and setting levers are yieldingly held in one extreme or the other of their rocking movement by a tension device which preferably consists of a detent 83 guided in a way 84 on the carrier and provided with a rounded nose which engages with a rounded face on the front arm of the setting lever, and a spring 87 arranged in said guide-way 84 and bearing with one end against the bottom of the same and with its opposite end against the back of said detent as shown in Figs. 9, 11 and 13. As the setting lever is rocked its rounded front end deflects the detent until the dead center between the highest opposing surfaces of those members have passed one another and then the detent operates to hold the setting lever and associated parts yieldingly in this changed position.

For the purpose of limiting the rocking motion of the setting lever and restoring lever any suitable stop means may be employed, those shown in Fig. 4 being satisfactory and consisting of stop shoulders 88, 89, formed on the heel of the restoring lever and adapted to engage with stop surfaces 90, 91 on the adjacent part of the rotary carrier.

The operation of this switch controlling mechanism and proper sequence is as follows:

When the steering mechanism is in its central or normal position the several parts of the controlling mechanism are in the position indicated in Figs. 3, 4, 5 and 6. As there shown, both switch shafts are turned so that their tumblers are all in a neutral position which permits the steering wheel to be turned in either direction and the car to be steered accordingly without affecting the signal lamps. If now it is desired to give a signal that the driver intends to make a full turn to the left then the left hand finger piece 56 is turned backwardly or toward the driver about one-quarter turn, whereby the respective locking tumbler is turned from the forwardly inclined position, shown in Fig. 6, to the rearwardly inclined position, shown in Fig. 7. Turning of this locking tumbler is however only possible when the steering wheel is in its central position, at which time the respective notch 69 of the locking rail 67 is above this locking tumbler and therefore provides the necessary clearance space in which this tumbler can turn. At all other times this tumbler is locked against turning so that the signal lamps cannot be lighted excepting when the car is running straight forward or substantially so. This will be evident upon examining Fig. 7, which shows the locking tumbler inclined backwardly and held in this position

by engagement of the same with the adjacent edge surface of the outer locking rail 67 due to partial turning to the left of the steering wheel. The same effect of holding the tumbler against turning would occur if the left locking tumbler were turned into a forwardly inclined position and the steering wheel were turned partially toward the right, in which case the notch 69 would be moved rearwardly out of register with the respective tumbler 71 and the latter would engage with the corresponding locking rail in rear of the notch 69.

If the steering wheel has been turned only to a small extent toward the left after having set the left switch for indicating a proposed left turn it is still possible to again straighten out the steering mechanism without opening the left switch and extinguishing the left signal lamps, thereby enabling a driver to maneuver to some extent before actually making the full turn as may be necessary at times in congested traffic. When, however, the driver continues to turn the steering wheel for completing the turn after effecting the initial part of this turn then the setting cam 80 of the setting lever engages with the salient part of the left restoring tumbler 72, which latter at this time stands in the path of this setting cam, whereby the front arm of the setting lever is raised and the rear arm thereof is depressed, as shown in Fig. 9, thereby lowering the restoring lever and carrying the restoring tappet 74 into line with the restoring tumbler 72 and carrying the clearing cam 75 into line with the clearing tumbler 73, said restoring tappet and clearing cam at this time being arranged in rear of the restoring tumbler 40 and clearing tumbler.

After the car has completed the turn to the left, straightening of the progress of the same is effected by reversing the movement of the steering wheel until the same again reaches its central or normal position. During the first part of such return movement of the steering wheel the restoring tappet of the restoring lever engages the restoring tumbler which at this time stands in its path, as shown in Fig. 11, and turns this tumbler forwardly out of the path of the restoring tappet, as shown in Fig. 13. While turning the restoring tappet into this position the companion clearing tumbler 73 is turned in unison therewith into a position in which its salient face stands immediately behind the clearing cam 75 of the restoring lever and in the path of said cam, as shown in Fig. 13. When the restoring tappet thus turns the restoring tumbler reversely the switch shaft upon which this tumbler is secured turns in the same direction, thereby causing the contacts of the respective switch to be separated and the lamps arranged in the circuit of this switch to be extinguished, whereby this

direction signal is terminated. Upon subsequently turning the steering wheel to the left to a moderate extent as frequently occurs while running a car without making a pronounced turn in that direction, the first effect is to bring the clearing cam of the restoring lever into engagement with the clearing tappet, as shown in Fig. 13, and upon continuing the turn of the steering wheel in this direction the clearing tumbler will deflect the clearing cam out of line with the clearing tumbler into the retracted position shown in Figs. 4 and 6, thereby also retracting the restoring tappet 74 and projecting the clearing cam 80 into line with the clearing tumbler 73. The parts are now restored to a position in which the signal lamp switches will not be affected upon turning the steering wheel in either direction.

Upon closing the right hand signal switch and lighting the corresponding lamps the operation of the controlling mechanism on the right hand side thereof is the same as that just described with reference to the parts on the left hand side for maintaining the right lamps burning until a full right turn has been made and the car has again straightened out, at the completion of which the lights are again extinguished.

It will now be evident that by the use of this signal controlling mechanism it is possible to light the lamps for signalling an intended turn to the right or the left, that such light will be maintained until the full turn has been effected and the car again straightened out, and that a partial turn followed by a straightening of the car will not operate to extinguish the lights, thereby avoiding the possibility of giving a confusing signal and eliminating danger in traffic.

If the switch when being set by the driver is not thrown fully into its extreme closed position the subsequent turning of the steering wheel will complete this turning by engagement of the trailing end of the gap in the respective locking rail with the partially turned locking tumbler and thereby ensure closure of the signal lamp circuit. By engaging the clearing tumbler with the clearing cams on the restoring lever the latter are pushed to one side when not in use and thereby avoids any clicking noise while the steering mechanism is used during the time that the signal lamps are out.

I claim as my invention:

1. A signal mechanism for an automobile steering mechanism having a stationary column and a rotatable steering post, comprising a support adapted to be mounted on said column, a switch shaft journaled on said support, locking, restoring and clearing tumblers arranged on said shaft and adapted to be turned thereby, a rotary carrier adapted to be mounted to turn with said steering post, a restoring lever pivoted on said carrier and having a re-

4. A signal mechanism for an automobile steering mechanism having a stationary column and a rotatable steering post, comprising a support adapted to be mounted on said column, a switch shaft journaled on said support, a carrier adapted to be mounted on a stationary part, a switch member having a plurality of tumblers, locking means arranged on the carrier and adapted to engage one of said tumblers, restoring means arranged on said carrier and 130

adapted to engage another of said tumblers, and clearing means mounted on said carrier and adapted to engage still another of said tumblers.

8. A signal mechanism for an automobile steering mechanism having a column and a steering post, comprising a support mounted on said column, two switch shafts journaled on opposite sides of said support and each having a locking tumbler, a restoring tumbler and a clearing tumbler, a carrier mounted to turn with said post; two locking rails arranged concentrically on said carrier around the axis of said post and one having a locking face and gap on one side of the post and adapted to cooperate with the locking tappet of one of said shafts and the other having a locking face and a gap on the opposite side of the post and adapted to co-operate with the locking tappet of the other shaft, and two trip devices arranged

on the carrier between the rails thereof and on opposite sides of the post and each trip device comprising a restoring member movable toward and from one set of locking, 25 restoring and clearing tumblers and having a restoring tappet adapted to turn the respective restoring tumbler and a restoring cam adapted to engage with the respective clearing tumbler, and setting members 30 mounted on said carrier between the rails thereof and on opposite sides of said post and movable toward and from said tumblers and having a connection with said restoring member for causing said members to 35 move in opposite directions and having a clearing cam adapted to engage the respective clearing tumbler for shifting said members into a normal position.

In testimony whereof I hereby affix my 40 signature.

WILLIAM A. ECKERT.
